(57) **CLAIM**

We claim the ornamental design for a pan lid, as shown and described in FIGS. 1–14.

DESCRIPTION

FIG. 1 is a perspective view of the pan lid shown with a pan body.

FIG. 2 is a side view of the pan lid with pan body shown in FIG. 1.

FIG. 3 is another side view of the pan lid with pan body shown in FIG. 1.

FIG. 4 is front view of the pan lid with pan body of FIG. 1.

FIG. 5 is a rear view of the pan lid with pan body of FIG. 1.

FIG. 6 is a top view of the pan lid with pan body of FIG. 1.

FIG. 7 is bottom view of the pan lid with pan body of FIG. 1.

FIG. 8 is an enlarged perspective view of the pan lid, shown without the pan body for completeness of illustration.

FIG. 9 is a side view of the pan lid shown in FIG. 8.

FIG. 10 is another side view of the pan lid shown in FIG. 8.

FIG. 11 is front view of the pan lid of FIG. 8.

FIG. 12 is a rear view of the pan lid of FIG. 8.

FIG. 13 is a top view of the pan lid of FIG. 8; and,

FIG. 14 is bottom view of the pan lid of FIG. 8.

The present application is directed to the design illustrated in the drawings. The broken line portions of the disclosure are for illustrative purposes only and form no part of the claimed design.
